UNITED STATES PATENT OFFICE.

HENRY A. CHURCH, OF PROVIDENCE, RHODE ISLAND.

ORNAMENTAL CHAIN.

SPECIFICATION forming part of Letters Patent No. 293,417, dated February 12, 1884.

Application filed November 13, 1882. (No model.)

To all whom it may concern:

Be it known that I, HENRY A. CHURCH, of the city and county of Providence, and State of Rhode Island, have invented a new and useful Improvement in Ornamental Chains; and I hereby declare that the following is a full, clear, and exact description of the same, reference being had to the accompanying drawings, form part of this specification.

10 This invention has reference to an improvement in that class of ornamental chains known in the art as "roller-chains"—that is to say, a chain made up by securing a large number of small rings or units side by side to form the width required, each set of which overlaps the next set lengthwise.

The invention consists in providing the units with two or more holes through which the binding-wires pass, so as to secure the same together and prevent the units from turning, and in the peculiar and novel construction of the end units, by which both edges of the chain can be made to correspond, as will be more fully set forth hereinafter.

25 Figure 1 is a perspective view of a short piece of roller-chain. Fig. 2 is a sectional view of a piece of roller-chain. Fig. 3 represents a number of side units in section, the corresponding side units provided with caps being indicated in broken lines. Figs. 4 and 5 represent ornamentations formed on the side units and corresponding caps. Figs. 6 represents a number of the central units provided with two or more holes, or holes of such 30 form as will firmly hold the units on the binding-wires. Fig. 7 is a sectional view of one form of a modification. Fig. 8 is another form 35 of a modification, in which the binding-wires are secured to the cap instead of to the units, and the unit is placed over the cap. Fig. 9 is a sectional view of a side unit on which a washer is secured, having two slots on opposite sides, through which the legs of the staple pass. The washer, with the staple, is secured 40 by closing the unit in a die, so as to retain the washer.

In roller-chains, when the chain is made up and colored, it requires to be polished. In polishing, the portions of the units exposed 45 will receive a fine polish, while the portions of the units out of the reach of the polishing device are not so polished. As long as the units

remain in the position in which they were when polished, the appearance of the chain is preserved. As soon, however, as the units or 55 any of them are partially turned, the appearance of the chain is injured by presenting in places the unpolished surface of the units.

I am aware that such units have before my present invention been provided with elongated holes, for the purpose of better securing the same against rotation, as is shown and described in Letters Patent No. 241,189, granted to me May 10, 1881. The first part of my present invention refers to holes constructed 60 to fixedly hold the units, in which the wires nearly fill the holes or the ends of the holes, as I find in practice that an elongated hole 65 may allow sufficient play to expose small portions of the units not polished.

In the drawings, A A are the central units; B B, the side units; C C, the caps secured in one set of the side units, so that the same correspond in appearance with the side units on the opposite side of the chain.

70 d d are wire loops or staples, which are secured within the closed side units, B, by solder, so that the two legs of the staples project. They are inserted into the holes formed in the central units, A A, and then pass through 75 holes formed in the end units, and are secured by twisting the ends of the staples together, as shown in Fig. 2; or the ends of the staples are passed through holes formed in the caps C and the ends twisted together, when the unit is secured over the cap, as is shown in Figs. 7 and 8. In either case the form and appearance of the side units on both sides of the chain correspond.

The side units, B B, as well as the caps C C, 80 for closing the units, may be ornamented by stamping in various ways, as is shown in Figs. 4 and 5.

The caps C C may be secured by pressing the metal of the units around the cap, or by 85 securing the same with solder.

The form of the cap and the unit when united must be of the same appearance and outline as the closed unit on the opposite side, so as to make both sides of the chain alike.

90 The holes e e may be formed in the central units separate or connected by a slot or other opening, as is shown in Fig. 6, but should be 95 of such form as to nearly fit the wire, so that

the units cannot turn and expose the unpolished portions of the units.

Having thus described my invention, I claim as new and desire to secure by Letters Patent—

- 5 1. In a roller-chain, the combination, with wires or staples for securing the links together, of the links, each of which is provided with a pair of apertures of such form as to nearly fit the wires or staples, and thus prevent the links from turning on the staples.

- 10 2. The combination, with the links provided with the apertures arranged to nearly fit the

staples, of the closed units B, the edge-cups provided with the caps C, and the staples d, said staples being secured at one end within the closed units and at the opposite end beneath the caps of the edge-cups, and the latter being arranged within said edge-cups, substantially as described.

HENRY A. CHURCH.
